1

When making radiographs for medical examination, a screen retaining stray rays is arranged between the patient and the film in order to improve the contrast. In order to prevent the raster structure of this screen from becoming visible on the radiograph, provisions are made to move the screen during the exposure of the film.

If the screen is caused to perform a rocking movement by means of a crank rotating at constant speed, the speed characteristic of the screen is substantially sinusoidal. If the X-ray tube with the aid of which the radiograph is taken is, moreover, fed by pulsatory current, it may occur that the screen pattern is yet reproduced on the film, owing to a stroboscopic effect which consists in that the shadow of the raster lamination is incident on the same lines in the plane of the film constantly at an instant at which the intensity of the X-rays reaches a maximum value. The probability of this occurrence is the greatest some time before and after the instant at which the speed of the screen movement has a maximum value, but also at certain accelerations stroboscopic effect may occur.

It should be noted that the raster may also be reproduced, not by stroboscopic effect, but by the fact that an instantaneous view is made accidentally at the instant at which the speed is zero.

The invention provides a means to prevent the pattern of the stray-ray screen from becoming visible on the radiograph owing to stroboscopic effect.

According to the invention, with a device to cause the stray-ray screen in an X-ray apparatus to perform a rocking movement with a sinusoidal or substantially sinusoidal speed characteristic, a periodical movement in the same direction, with higher frequency and preferably smaller amplitude is superimposed on the initial movement of the screen.

An excellently suitable solution of the problem in view is obtained, if the frequencies of the initial motion and that of the superimposed motion are incommensurable relative to one another.

However, even if the frequency of the superimposed motion is a whole multiple of that of the initial motion, an appreciable improvement is obtained, since even then the time intervals in which the speed maxima occur and in which the speed varies little are replaced each by a series of intervals having great relative speed variations.

Thus the probability of disturbance owing to stroboscopic effect is reduced, since the reproduction of the screen pattern on the film is made not by the simple occurrence of this effect, but

only if it also prevails long enough to permit the X-rays of producing a marked blackening of the film. If the time intervals in which coincidence occurs are shortened strongly, the intervals may be repeated more often without the occurrence of the stroboscopic effect.

The idea of the invention may be carried into effect in various ways. For example, the moving force may be supplied by two motors, of which one supplies the initial movement, the other the superimposed movement, the two motors being connected with the screen via a differential gear. By using asynchronous motors in this manner or in a similar manner, the frequencies of the initial movement and of the superimposed movement are incommensurable relative to one another. The two electric motors may, as an alternative, be replaced by a single motor which provides one movement, for example, the initial movement of the screen, the other movement being derived, for example, by means of planet gear from the first movement. In this case, it is true, the frequency of the superimposed movement is a whole multiple of that of the initial movement, but this disadvantage will mostly be balanced by the advantage of more simple driving gear.

In order that the invention may be readily carried into effect, it will now be described in detail with reference to the accompanying drawing.

30 Referring to the figure, reference numeral 1 designates a stray-ray screen, which is connected with a connecting rod 2, which moves in the glide sleeves 3 and 4. With this rod is connected at point 5 a lever so as to be pivotable; by means of crank mechanisms known per se the desired movements of the screen are given at the ends 7 and 8 of this lever. These movements, which have a sinusoidal or substantially sinusoidal characteristic may be synchronous or asynchronous.

40 By choosing the frequencies and the amplitudes of these component movements, the condition of movement provided by the superimposition may be varied within wide limits.

45 The use of the invention detracts by no means from the conditions occurring when the instant of a short exposure does not differ much from the instant at which the direction of the movement reverses. On the contrary, owing to the superimposed movement even in this case the statistic probability of a sufficient speed of the screen will be greater or the time during which the speed is so low that the screen is substantially stationary, will be shorter.

What we claim is:

55 1. A device for rocking a stray-ray screen in

2

an X-ray apparatus comprising first means for imparting substantially sinusoidal periodic movement to the stray-ray screen, and second means for imparting to said screen a periodic movement having a higher frequency and the same direction as the initial movement imparted by said first means and superimposed thereon.

2. A device as claimed in claim 1 in which the superimposed movement has a smaller amplitude than the initial movement.

3. A device as claimed in claim 1 in which the frequencies of the initial movement and of the superimposed movement are incommensurable relative to one another.

4. A device as claimed in claim 1, in which said first and second means each comprise a motor, and a differential gear connects the motor to said screen.

5. A device for rocking a stray-ray screen in

an X-ray apparatus comprising a displaceable rod connected to said screen, a lever pivotally secured at its center to said rod, first means connected to one end of said lever for imparting substantially sinusoidal periodic movement thereto, and second means connected to the other end of said lever for imparting thereto a periodic movement having a higher frequency, a smaller amplitude and the same direction as the movement imparted by said first means.
